CLAIM

The ornamental design for a security light, as shown and described.

DESCRIPTION

FIG. 1 is a front, bottom and left side perspective view of a security light showing my new design.

FIG. 2 is a rear, top and right side perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The portions of the security light shown in broken lines form no part of the claimed design.
